UNITED STATES PATENT OFFICE.

ALDAS S. RIDGLEY, OF BOSTON, MASSACHUSETTS.

BONNET-FASTENER.

1,376,039.

Specification of Letters Patent. Patented Apr. 26, 1921.

Application filed February 17, 1920. Serial No. 359,391.

To all whom it may concern:

Be it known that I, ALDAS S. RIDGLEY, a citizen of the United States, residing at Boston, in the county of Suffolk, State of Massachusetts, have invented certain new and useful Improvements in Bonnet-Fasteners; and I do hereby declare the following to be a full, clear, and exact description of the invention, such as will enable others skilled in the art to which is appertains to make and use the same.

This invention relates to locks and latches, and more especially of that type intended for fastening an automobile hood or bonnet closed over its engine; and the broad object of the same is to provide a device of this kind with a lock which can be operated by a key or otherwise before the fastener can be released so that the hood can be opened.

The invention consists primarily in a two-part fastener whereof one part is pivoted to the frame and the other is spring-pressed into hooked engagement with the hood, together with means controlled by a lock for preventing the telescopic distention of the parts to permit unhooking. The invention consists specifically in the means for carrying out this broad idea, and one successful embodiment thereof is described below and shown in the drawings wherein:

Figure 1 is a side elevation showing the fastener in position to lock the hood closed.

Fig. 2 is an enlarged section through the fastener on about the line 2—2 of Fig. 1, while Fig. 3 is a similar section at right angles, on the line 3—3 of Fig. 2.

Fig. 4 is a collective view illustrating certain parts.

Fig. 5 is a sectional detail on about the line 5—5 of Fig. 2, showing a slight modification.

Pivoted at P to the frame F of the machine is the lower member of this fastener which is telescopically mounted within the upper member as will be described. The latter has finger grips G by which it can be raised to draw its hook H out of an eye I carried by the hood or bonnet B, but when the hook and eye are engaged as seen in Fig. 1 the hood is drawn down onto the frame by a spring within the fastener yet to be described. When access to the engine is desired, the usual course is to hook the fingers under the grips G and raise the upper member of the fastener so as to disconnect it from the hood, and then turn it down on

its pivot P. By the present invention I propose to lock the device so that it cannot be so raised until it is unlocked, and I have employed an ordinary cylinder lock L for this purpose, whose details of construction are unimportant. However, any form of lock, even one working on the permutation principle, might be employed.

The lower and inner member of the telescopic fastener is a plunger 1 pivoted at its lower end at P to the frame F, and this plunger by preference has an angular body herein shown as square, and two pins 2 and 3 through the body at proper points. The upper and outer member of the fastener consists of a barrel 4 carrying the finger grips G at its sides and closed at its upper end by the lock L referred to, with its lower end open and preferably internally shouldered as at 5. This member also includes an upstanding tubular guide 6 having a flanged base 7 borne upward against said shoulder by a nut 8 which preferably has notches or openings for a spanner wrench by means of which it may be screwed into the lower end of the barrel as seen in Fig. 3. Set screws 9 may be employed if desired, passing through the wall of the barrel from that side next the hood, for holding the nut 8, flanged base 7, and perhaps also the lock L against rotation. The bore 11 of the guide 6 is preferably angular, being shown herein as square so as to slidably receive the plunger 1, and said guide is also provided with a longitudinal slot 16 extending completely across it through said bore and out its upper end, in which slot the ends of the pins 2 and 3 project and may move. A washer 12 surrounds the guide just beneath the lower pin 2, and a stout expansive spring 13 is coiled around the guide between said washer and the base 7, its tendency being to push upward on the pin and downward on the base and therefore to telescope the two members so that they shall normally collapse. The lower member being pivoted at P, thus produces a constant tendency of the upper member to descend, with the result that the hook H which has a rather long bill will be borne normally downward into the eye I on the hood, and the latter will be drawn down onto the frame with yielding pressure which permits the slight movements necessary in the travel of the automobile. The upper end of the guide is preferably reduced as at 14 and shouldered as at 15 for

a purpose yet to appear. The guide rises throughout a little more than half the length of the barrel, and the relative proportion of parts may well be about that shown in Fig. 2.

5 The lock L needs no description, but as herein shown it is of the type which is operated by a key, and 20 designates the keyhole. When the key is inserted and turned, it is necessary that it shall turn a shaft 21 de-

10 pending below the lock casing, and on the shaft is mounted a gear or, as shown in Fig. 4, a toothed segment 22. The teeth thereof are adapted to mesh with those in a curved rack 23 formed around and within the upper

15 end of a wing 24 rising rigidly from a locking ring 25 which is swiveled on the upper end of the guide 6 and whose opening has notches 26 adapted to aline with the projecting ends of the pin 3. Such alinement is

20 obviously produced by turning the key in the proper direction, whereas when it is turned in the opposite direction the entire ring is rotated on the guide, its movement either way being through about 90°.

25 While any suitable means may be employed for mounting the ring swivelly on the guide, I prefer to slip it over the reduced upper end 14 thereof, bear it down onto the shoulder 15, and apply a collar 35

30 which has internal notches 36 adapted to be set in alinement with the slot 16 so that the collar shall not interfere with the relative movement of the pin therein. As seen in Fig. 4 this collar is internally threaded as

35 at 37 to engage threads 38 with which the reduced upper end 14 of the guide may be provided, but this means of fastening the collar 35 may be replaced by other means, such as the set screw 39 shown in Fig. 5 or a

40 key of any appropriate form which could be easily inserted when the parts are assembled.

Assuming now that the operator desires to unlock the device and release and raise 45 the bonnet or hood. He inserts his key in the hole 20 and turns the shaft 21 so that the gear or segment 22 swings the wing 24 through about 90°. This turns the locking ring 25 until its notches 26 aline with the slot 16 and the ends of the pin 3. Then he may grasp the finger grips G and lift the barrel so as to disengage the hook H from the eye I. As the barrel rises, it carries with it the guide 6 and the ring 25 swiveled thereon, but it causes the relative descent of the plunger within the bore of the barrel, which is permitted because the ends of the pin 3 may now move downward. Meanwhile also the pin 2 and washer 12 move downward, and therefore the spring 13 is compressed. It follows that when the operator releases his hold on the fastener the spring expands, and therefore when he desires to again fasten the hood closed he must draw 60 upward on the grips to compress the spring

before he can engage the hook with the eye. To lock the parts in this condition, he turns the key to revolve the locking ring about 90°, when the key can be withdrawn. Surely one and possibly both of the fasteners on 70 each side of the hood should be equipped in this manner if the owner of the car desires effectively to prevent access to the engine and other parts under the bonnet.

What is claimed is:

1. An automobile bonnet fastener composed of two parts telescopically connected and including a spring drawing them normally toward each other; combined with an element rotatably mounted in one part and 80 adapted to be turned into engagement with the other to prevent the distension of the parts, and a lock controlling the turning of said element.

2. An automobile bonnet fastener composed of a plunger and a barrel connected for relatively telescopic but not rotary movement, and a spring drawing the plunger normally into the barrel; combined with an element rotatably mounted within 90 the barrel and adapted to be turned into engagement with the plunger to prevent its withdrawal, and a lock controlling the turning of said element.

3. In an automobile bonnet fastener, the 95 combination with an angular plunger, a barrel having an internal upstanding guide with an angular bore slidably inclosing said plunger, and a spring drawing the plunger normally into said guide; of a locking ring 100 swiveled on the inner end of the guide and having means whereby it may be turned into engagement with the plunger to prevent the withdrawal of the latter, a lock in the upper end of the barrel, and connections 105 between it and said ring.

4. In a fastener of the class described, the combination with a plunger adapted to be pivoted to one element and having two pins through its body; of a barrel having exterior means adapted to be engaged with another element and an internal upstanding guide inclosing said plunger and slotted for the ends of its pins, an expansive spring between the lower pin and the base of the 115 barrel, a locking ring swiveled on the upper end of the guide and having notches adapted to be set in alinement with said slot, a lock in the upper end of the barrel, and means connecting it with said ring.

5. In a fastener of the class described, the combination with a plunger adapted to be pivoted to one element and having two pins through its body; of a barrel having exterior means adapted to be engaged with another element and an internal upstanding guide inclosing said plunger and slotted for the ends of its pins, an expansive spring between the lower pin and the base of the 125 barrel, a locking ring swiveled on the upper 130

end of the guide and having notches adapted to be set in alinement with said slot and an upstanding wing having a curved toothed rack, a lock carried by said barrel, and a 5 toothed segment actuated by the movements of the lock and engaging said rack for turning the ring.

6. In a fastener of the class described, the combination with a plunger adapted to be pivoted to one element and having two pins through its body; of a barrel having exterior means adapted to be engaged with another element and an internal upstanding guide inclosing said plunger and slotted for 15 the ends of its pins, an expansive spring between the lower pin and the base of the barrel, the upper end of said guide being reduced, a locking ring rotatably mounted on the reduced end and having internal notches 20 adapted to be set in alinement with said slot and an upstanding peripheral wing, a locking collar removably secured to said reduced end above the ring and having similar internal notches, a lock in the upper end of 25 said barrel, and connections between it and said wing, for the purpose described.

7. In a fastener of the class described, the combination with a square plunger adapted to be pivoted at its lower end to one element 30 and having a pin through its upper end; of a barrel loosely surrounding said plunger and having an internal upstanding tubular guide with a square bore slidable on said plunger, the guide being slotted for the 35 extremities of said pin, a locking ring swiveled on said guide and having internal notches through which said extremities pass when the notches aline with the slot, a lock

in the upper end of the barrel, and connections between it and said ring. 40

8. In a fastener of the class described, the combination with an angular plunger adapted to be pivoted at its lower end to one element and having a pin through its upper end; of a barrel loosely surrounding said 45 plunger and having an internal upstanding tubular guide with an angular bore slidable on said plunger, the guide being slotted for the extremities of said pin, a locking ring swiveled on said guide and having internal 50 notches through which said extremities pass when the notches aline with the slot, a rack of teeth carried by said ring and curving through an arc, a lock in the upper end of said barrel, and a toothed member carried 55 by the lock and actuated by its movements, its teeth being in mesh with those of said rack.

9. In a device of the class described, the combination with an upright barrel whose 60 lower end is open and internally shouldered and threaded, a tubular guide within the barrel having a base flange fitting its lower end against the shoulder therein, and a nut screwed into said lower end against the 65 flange; of a plunger slidable through said guide, means for drawing it inward therein, and lock-controlled means for preventing it from being drawn outward.

In testimony whereof, I affix my signature, in the presence of two witnesses. 70
